[57] CLAIM

The ornamental design for the front face of a vehicle instrument panel, as shown and described.

DESCRIPTION

FIG. 1 is a front perspective view of a front face of a vehicle instrument panel constructed according to our novel design; FIG. 2 is a front perspective view from the left side of the novel design of FIG. 1;

FIG. 3 is an enlarged fragmentary front view of a center section of the novel design of FIG. 1;

FIG. 4 is an enlarged fragmentary front view of a left side section of the novel design of FIG. 1; and,

FIG. 5 is an enlarged fragmentary front perspective view, from the left side, of a left side section of the novel design of FIG. 1.

The undisclosed right side of the panel is a mirror image of the left side.

Those portions of the drawing figures shown in broken lines depict environment and are not to be considered part of the novel design being claimed.
